(No Model.)

J. F. STUCKERT.

FIRE PROOF ROOF, FLOOR, &c.

No. 349,670.

Patented Sept. 21, 1886.

UNITED STATES PATENT OFFICE.

J. FRANKLIN STUCKERT, OF PHILADELPHIA, PENNSYLVANIA.

FIRE-PROOF ROOF, FLOOR, &c.

SPECIFICATION forming part of Letters Patent No. 349,670, dated September 21, 1886.

Application filed October 8, 1885. Serial No. 179,354. (No model.)

To all whom it may concern:

Be it known that I, J. FRANKLIN STUCKERT, a citizen of the United States, residing in the city and county of Philadelphia, State of Pennsylvania, have invented a new and useful Improvement in Fire-Proof Roofs, Floors, Ceilings, &c., which improvement is fully set forth in the following specification and accompanying drawings, in which—

10 Figure 1 represents a transverse vertical section of a building to which my invention is applied. Figs. 2, 3, 4, and 5 represent portions of the same on enlarged scales.

Similar letters of reference indicate corresponding parts in the several figures.

My invention consists of means for protecting roofs, floors, ceilings, walls, &c., from fire, and extinguishing fire, as will be hereinafter set forth.

20 Referring to the drawings, A represents a floor, and B a ceiling. Below the ceiling are convex or arched gutters C, consisting of plates of corrugated metal or other suitable material, secured to the beams or girders D in any suitable manner, forming channels or passages, into which water, steam, acid, or other cooling or fire-extinguishing medium is introduced from pipes E, which are connected with a pipe, F, the latter being in communication with a pipe, F', or system of pipes, main G, or other source

30 of supply, or a branch, H, to which a fire-engine or pump may be attached. As shown in the drawings, the pipe E opens into the gutter C at the highest part thereof, so as to direct the stream to both sides of the curve. The beams or girders are made either hollow or have tubes or sections of tubes connected with them, which form receptacles for water, said receptacles being in communication with the

40 pipe F'. The column J is made hollow and connected with the pipe F' by a suitable branch, J', so as to be in communication with the main G or place of supply, and be filled with water or other fluid, whereby it is protected from heat. Said column may have perforations, so as to permit the fluid to escape therefrom and enter the apartment where the fire exists.

45 K represents the door of an apartment, an elevator, &c., the same being made hollow, and 50 being in communication with the pipe F' by a suitable pipe, F'', there being an opening in

both the top casing and the top of the hollow door, so that the door may when closed be filled with fluid and readily opened and closed. The gutters C not only direct the water against the metal bearings to protect them from heat, but also serve to catch any leak from the floor or roof above.

55 Where the beams, girders, or metal joists and gutters are combined, or the gutters divided by a web, small openings may be made wherever desired, to admit of the water or fluid circulating in any desired direction. In cases where the hollow girders or columns are large, the same may be partly filled by a hollow or solid 60 body or core, so as to decrease the fluid-space of said girders or columns.

65 To the beams or girders may be secured gutters L, which are so disposed at the ends of the gutters C as to receive the water or fluid 70 admitted therein, or leak or moisture from the floor or roof, as shown in Fig. 3 and in the right hand of Fig. 2 and left-hand part of Fig. 4. When the pressure of fluid admitted to the gutters C is sufficient, the fluid will overflow at 75 the gutters L and so be directed into the apartment, serving to extinguish fire therein.

70 In place of the pipes E communicating with the gutters C, short pipes E', (see Fig. 1,) leading from the pipe F and opening into the apartment, may be employed. It may also be well to use both the pipes E and E'. A check-valve, 80 M, is connected with the pipe F', to prevent the return of water to the main when a tank is employed for supply of water. A check-valve, 85 N, is connected with the pipes E, for the purpose of distributing the water either to the gutters C or other parts of the building, as desired.

Having thus described my invention, what I claim as new, and desire to secure by Letters Patent, is—

1. The ceiling B, in combination with the curved gutter C and girders D D, the said gutter having an inlet-pipe, E, opening into the same at its highest part, substantially as and 95 for the purpose set forth.

2. The floor A, in combination with the ceiling B and gutter C, the latter extending under the surface of the said ceiling, and forming a single chamber between each adjacent pair of 100 girders, substantially as described.

3. A ceiling and a gutter below the same, in

combination with the pipe E, which is in communication with said gutter, substantially as and for the purpose set forth.

4. A hollow beam or girder provided with 5 the gutter L, substantially as and for the purpose set forth.

5. A ceiling with a gutter below the same, in combination with a trough or gutter attached to the supporting-beam, substantially as de-
10 scribed.

6. A ceiling and a gutter beneath the same,

in combination with a supply-pipe and the check-valve M, substantially as and for the purpose set forth.

7. A ceiling and a gutter beneath the same, 15 in combination with the pipe E and a supply-pipe, substantially as and for the purpose set forth.

J. FRANKLIN STUCKERT.
